CALVIN N. MILLER, OF MUNCIE, INDIANA, ASSIGNOR TO GLASCOCK BROTHERS MFG. COMPANY, OF MUNCIE, INDIANA, A CORPORATION OF INDIANA.

BOTTLE REFRIGERATOR.

Application filed October 1, 1925. Serial No. 59,786.

My invention relates to improvements in refrigerators for bottles and particularly to dispensing refrigerators for pop bottles.

One of the objects of my invention is to provide a refrigerator for cooling and dispensing pop bottles which may be so constructed as to permit the use in said refrigerator of a particular type of bottle only, so that the pop bottler may, for the purpose of stimulating trade in his particular goods, distribute pop bottle refrigerators to his dealers and be assured that only his goods will be used in the refrigerator.

Another object of my invention is to provide a refrigerator for pop bottles which while being efficient both in cooling the goods, and in dispensing the bottles, may be manufactured at a minimum expense.

Other objects and advantages of the invention will appear more fully hereinafter.

For the purpose of disclosing my invention I have illustrated one embodiment thereof in the accompanying drawings in which

Fig. 1 is a perspective view of a refrigerator embodying my invention;

Fig. 2 is a partial transverse section of the box illustrated in Fig. 1;

Fig. 3 is a longitudinal section thereof;

Fig. 4 is a sectional view on the line 4—4 of Fig. 3, and

Fig. 5 is a sectional view showing a modification of the bottle propeller operating means.

In the structure illustrated I provide a suitable frame or box structure 1 supported on legs 2 and within which is a suitable liner 3 for the sides and bottom, the space between the liner 3 and the side panels 4 and bottom panel 5 being filled with cork or other desirable heat insulating material.

Within the enclosure thus formed I provide an ice receptacle 6 which extends from front to back of the enclosure and has its side walls secured at their top to cross braces 7, which braces support a cover 8 for the ice chamber. The side walls of this chamber 6 are provided with suitable openings 9 through which the water of the melted ice or the brine mixture or other cooling medium may escape to the bottle compartments 10 and 11 arranged on each side of the ice chamber. The compartments 10 and 11 are divided into a series of bottle receiving channels 13, 14 and 15. The side walls 16 of these channels do not extend to the top of the compartment so that all of

the channels are laterally liquid communicating thereby providing in each channel a liquid bath in which the bottles maintained in the channels are substantially emersed, the level of the liquid being maintained at a point just below the top of the bottle. I have illustrated various types of channels which may be formed and used in my structure. The channels 13 are of a type wherein any type of bottle may be passed therethrough, the side walls being substantially straight and the channels being adapted to support the bottles in a vertical position and the bottles being adapted to be fed through the channels in a lateral series from front to back.

The channels 14 and 15 are of types adapted to receive particular types of bottles and to this end are keyed so that their keys will engage in keyways formed in the bottle to prevent any but bottles having keyways or having a configuration to coincide with the keys of the channel being fed through the channel. There are various ways of forming these keys and I have illustrated in the drawings one manner of keying the channels which consists in the turning in of the upper edge of the channels to form flanges such as 17, which flanges are adapted to fit in coinciding restricted portions in the bottles. The channels 14 are shown as being keyed to receive only the type of bottle in which "Coca Cola" is now being dispensed and which, at its lower end, is provided with a restricted portion flaring out into the bottom of the bottle. By providing the flanges 17 at a height sufficient to coincide with this restricted portion and thereby making the neck of the channel narrower than the remaining portion of the channel, only a bottle having substantially the configuration of a "Coca Cola" bottle may be fed through the channel. The compartment 15 in like manner is arranged to receive only the bottles containing "Nu-Grape". This type of bottle is provided with a restricted waist and the flanges 17 are inverted at a greater height to coincide with this restricted waist. It is therefore apparent that these channels are keyed or irregularly shaped to receive bottles having a configuration to conform to the irregularities in the channel so that only specified bottles may be delivered or passed through the channels. The bottles are adapted to be inserted at the rear end of the channel at which point of course the flanges would be left off and

are adapted to be inserted in the channel axially while being fed through the channel in a lateral series. They are adapted in the same manner to be removed from the front 5 end of the channel axially and to this end the compartment and channels are closed at their top by suitable closure members 18 fitting within the frame and secured in position. An intake opening 19 is provided at the 10 rear end through which opening the bottles may be dropped into the channels and a suitable outlet opening 20 is provided at the forward end through which the bottles may be removed, the opening 19 being closed by a 15 hinged cover 21 and the opening 20 being closed by a hinged cover 22. The bottles are propelled forwardly serially in their respective channels by propellers 23 adapted to lie vertically when in retracted position at the 20 rear end of the channel and provided with suitable wings 24 to embrace, or partially embrace, the sides of the bottle. These propellers are hingedly mounted as at 25 to the frame, their lower end being free so that 25 the propeller may have a swinging or reciprocal movement and when swung forward against a bottle that has been inserted through the opening 19 into the channel will propel this bottle forward, and when swung rearwardly or back to its substantially vertical position will leave sufficient clearance between the bottle moved forward and the propeller for the insertion of a new bottle through the opening 19.

30 In order that the bottles may be moved forward automatically by the opening of the door the propellers are connected with the hinged door 22 by suitable connecting rods 26 hingedly secured at their forward ends to 35 the door 22 and being inturned at their rear ends to engage in an arcuate slot 27 formed in two of the wings 24. This slot is of such length that the door 22 may be partially opened without operating the propellers, but 40 when opened to its fullest extent will cause the propellers to move forward and thus propel the line of bottles maintained in the channels forwardly.

In operation the bottles are inserted into 45 the channels through the opening 19 and are moved forwardly until the channel is completely filled. In dispensing the bottles the operator is supposed to first remove a chilled bottle and then insert a warm bottle at the 50 rear of the channel so that when the hinged cover 22 is again opened the bottles will be fed forward. If by any chance he inserts a warm bottle before he receives a chilled bottle there is not sufficient room for the bottles 55 to move forward, but due to the lost motion connection between the hinged door 22 and the propellers 23 the door can be sufficiently opened to permit the removal of a bottle.

In Fig. 5 I have illustrated a modified operating means for the propellers wherein the

propeller is moved forwardly by the opening of the hinged closure 21. In this construction the closure member 21 is hinged on the same hinge support as the propeller 23 and is provided with an arcuate finger 28 adapted, after the door has been opened a sufficient distance, to engage behind the propeller 23 and swing the same forward by a continued opening movement of the door. This permits the door or cover member 21 to be opened sufficiently to permit the insertion of a bottle in a channel and then by a continued opening movement operate the propeller to force the bottle forwardly through the channel.

I claim as my invention:

1. A bottle refrigerator including a bottle channel irregular in cross section at that portion through which the body of a bottle passes to permit the passage therethrough only of a bottle having a configuration in the body portion thereof to coincide with the irregular shape of said channel and means for propelling bottles through said channels.

2. A bottle refrigerator including a bottle channel constructed to receive and permit bottles to pass therethrough in side by side relation, the walls of said channels having keys at that portion through which the body of the bottle passes arranged to fit keyways formed in the bottles to prevent the passage through said channel of any bottles except those having a body of a particular type.

3. A bottle refrigerator including a bottle channel constructed to receive and permit the bottles to pass therethrough in side by side relation, the side walls of said channel being irregularly shaped at that portion through which the body of the bottle passes to prevent the passage through said channel of any bottles except those having a configuration to coincide with said irregular shaped walls.

4. A bottle refrigerator including a bottle channel having receiving and delivery openings at its rear and front ends for receiving and delivering the bottles axially, the bottles being adapted to pass through the channel in a lateral series, a reciprocal propeller at the rear end of said channel, a closure member for the delivery opening of said channel, and a lost motion connection between said closure member and said propeller for operating the propeller by the opening and closing of the closure member while permitting the closure member to be partially opened without affecting the propeller.

5. A bottle refrigerator including a bottle channel through which the bottles are adapted to be propelled in a lateral series and having an opening through which the bottles are adapted to pass axially, a reciprocal propeller at the rear of said channel for engaging and propelling the bottles forwardly through said channel, a closure member for said opening

having a lost motion connection with the propeller for operating the same to propel the bottles forwardly upon the opening of the closure member while permitting the closure member to be partially opened without affecting the propeller.

6. A bottle refrigerator including a bottle receiving channel having a delivery opening at one end and a receiving opening at the other end through which the bottles are axially removed and inserted, the bottles being adapted to pass through the channel in a lateral series, a reciprocal propeller at the rear

end of said channel, a closure member at the forward end of said channel and means connecting said propeller with said closure member to cause said propeller to be reciprocated by the operation of said closure member, said connecting means permitting an opening movement of the closure member without moving the propeller.

In witness whereof, I, CALVIN N. MILLER, have hereunto set my hand at Bradenton, Florida, this 23rd day of September, A. D. one thousand nine hundred and twenty-five.

CALVIN N. MILLER.
